UNITED STATES PATENT OFFICE.

JEFFERSON B. SCEARCE, OF CHILlicothe, OHIO, ASSIGNOR TO BENJAMIN D. MINER, OF INDIANAPOLIS, INDIANA.

INVALID-BED.

SPECIFICATION forming part of Letters Patent No. 520,576, dated May 29, 1894

Application filed March 18, 1893. Serial No. 466,692. (No model.)

To all whom it may concern:

Be it known that I, JEFFERSON B. SCEARCE, a citizen of the United States, residing at Chillicothe, in the county of Ross and State of Ohio, have invented certain new and useful Improvements in Invalid-Beds; and I do hereby declare the following to be a full, clear, and exact description of the invention, such as will enable others skilled in the art to which it appertains to make and use the same.

My invention relates to improvements in invalid beds, but more particularly to that class wherein an elevating device is used to move the covered frame upon which the invalid rests, so as to vary the position of the patient in order to provide for the various conditions required in attendance upon the sick.

The invention has special reference to the manner of constructing the covered frame, and the manner in which it is adapted to operate in connection with an improved elevating device.

The invention consists in certain improved features of construction and combinations of parts all as will be hereinafter more fully described and particularly pointed out in the claims at the end of this description.

In the accompanying drawings Figure 1 is a perspective view of an invalid bed showing the covered frame elevated to its highest point. Fig. 2 is a perspective view of the bed showing the covered frame tilted so as to elevate one side. Fig. 3 is a detail showing the construction and manner of uniting the ends of the frame. Fig. 4 is a side elevation of the bed, showing the covered frame lowered in full lines, and the various positions it may assume in dotted lines. Fig. 5 is a detail perspective view of the under side of the covered frame, showing the manner of securing the flap. Fig. 6 shows the bed and frame folded for shipment or storage; and Fig. 7 is a detail showing the manner of passing the hoisting rope through the shaft.

Like letters of reference are used to denote like parts in each of the several views.

In the drawings A, represents the bedstead, which is provided with the usual posts A', at the head and foot; the invention being shown as applied to a folding or knock-down bed, which may be constructed of either wood or

iron and which has the necessary braces a, for holding the legs in proper position when set up.

The hoisting mechanism B, is secured to the posts A', at the head of the bed and the shaft B', thereof extends from one side of the bed to the other. Through the shaft B', the hoisting ropes b, b, pass. Said shaft is mounted at one side of the bed, preferably the head, in a suitable bracket B², and at the other side of the bed a bracket or bearing B³, is adapted to receive the shaft B', so as to support it in proper position. One end of the shaft B', is provided with a large gear wheel C, at its outer end, which is in turn engaged by a small pinion C', also carried on a suitable stud or shaft c, which is adapted to receive the handle c', by which the hoisting of the covered frame D, is accomplished. Any retrograde movement of the frame D, after it has been elevated, is prevented by the pawl b', engaging the gear wheel C, so as to lock it against such movement. The arrangement of the hoisting gearing and locking pawl at one side of the bed is preferable, and in fact necessary if the patient is to be moved by a single attendant, as by this arrangement all parts are under direct control.

At or near the top of the posts A', at the head and foot of the bed are small sheaves or pulleys a', and at or near the bottom of the posts at the foot are similar sheaves or pulleys a². Over these pass the hoisting ropes or chains b, b. These ropes or chains pass through perforations b³, and around the shaft B', in such a manner as to give a sufficient bight or lock to the rope or chain, so that it will not slip when the power is applied through the medium of the handle c'. From the shaft B', one end of the ropes b, b, passes to the end of the frame D, after passing over the pulleys or sheaves a', at the head of the bed. The other end passes under the bed, thence around pulleys or sheaves a², at the bottom, and a', at the top of the posts at the foot of the bed, to the foot of the frame D. A snap hook G, of any suitable construction is secured to the ends of the ropes b, b, and these hooks enter the eye-bolts F, which fasten the frame D, together at their ends. The frame D, which is covered with canvas or

other suitable material E, consists of the end bars or frames D', and the side bars D², so connected at their corners that they are readily separated. A supplemental frame d, at 5 the "head end" of the frame is hinged in any suitable manner to the main frame D, and consists of the side bars d', and the end bar d², secured in a similar manner to the frame D.

The covering E, of canvas or other suitable 10 material has its sides and ends hemmed, being cut out at the corners so that the side and end bars of the main and supplemental frames D, d, may be inserted. At a proper 15 point in the center of the covering a hole is cut for the convenience of the patient, and may be covered by a supplemental flap e, having one edge stitched to the covering and the other end free, but adapted to be secured so that it will be taut when not required to be 20 let down. This is accomplished by means of a rod H, which passes through the eye bolts which are secured to the side bar of the frame D, and through the hem in the flap e, which is cut out to receive one of the eye-bolts. The 25 making the flap taut is very necessary to the comfort of the patient.

The manner of securing the frame together by means of eye-bolts F, as shown in the drawings, is of great importance and practical 30 utility, for by such an arrangement the soiled canvas or other covering may be quickly removed for the purpose of washing, and readily replaced. The bars are secured together by eye-bolts only and when these are removed 35 the bars are free to be drawn out.

As constructed by me, the supplemental head frame d, is covered by the same canvas as the main portion of the frame, so that the whole covering is in one piece. The supplemental head frame d, is further provided 40 with pivoted braces d², so that the patient may be bolstered up when the frame is elevated too high for the ropes to hold it in an inclined position, or when a more erect sitting posture 45 is desired. If it is desired to change the position of the patient it is obvious that the snap hooks must be inserted in the proper eye-bolts, and it is often necessary to make these changes rapidly. A readily detachable 50 connection such as is afforded by a snap hook is oftentimes absolutely essential. After the desired connection of the hoisting ropes has been made with the frame D, the attendant can easily bring the frame with the patient 55 lying thereon into the required position with no strain incident to lifting.

The folding or "knock down" feature of the bed frame is of great utility in places where space is an element which must be 60 taken into account. The posts A', are fastened by iron braces pivoted to the body of the bed A, and are adapted to fold and exactly fit underneath the same, so that the whole when knocked down may be folded 65 into compact form for the purpose of transportation or storage.

When it is desired to remove the covering

E, for washing or repair, the eye-bolts F, are withdrawn, and the bars constituting the frame D, and head frame d, may be withdrawn from the hems, after removing the slip pin from the hinge between the main and supplemental frames, the hem being slit at that point to permit of access to the hinge. 70

To replace the covering, the parts of the 75 frames are passed through the hems in the sides and ends of the canvas as follows:— The side pieces of the short frame being detached from the main frame are passed through the side hems of the canvas from the 80 head end and through a slit in the hem opposite the hinge. The side pieces of the main frame are then passed through the same slit in the hem until the hinge is opposite the slit. The short pieces are then attached to 85 the long side pieces by replacing the slip pin in the hinge. The foot piece of the long frame and the head piece of the short frame are then passed through the hems at the ends of the canvas and the parts are joined together at the corners by passing the eye-bolts therethrough and securing the nuts on the opposite side. The canvas thus provides a continuous covering extending over the main frame from the foot to the hinge and thence 90 up over the short head and shoulder supporting frame. 95

When it is desired to shift the position of the patient for any purpose and it becomes necessary to shift the connections of the hoisting ropes, it may be done with ease and rapidity by simply disengaging the snap hooks from the eye-bolts with which they may be connected and instantly connecting the same with other bolts as may be desired. The four 105 pieces composing the main or hammock frame being connected at the corners by detachable eye-bolts, and the short supplemental frame or head and shoulder support consisting of three pieces similarly connected at the corners thereof and having the free ends of their side pieces connected to the main frame by slip pin hinges, provides not only a simple and inexpensive construction, but one which may be readily taken apart to permit a new 110 piece to be substituted in the event that any part becomes broken, the canvas covering being easily and quickly removed to permit of such repairs. 115

From what has been said it will be seen 120 that quick adjustment of the frame, and ready removal of the covering are accomplished in an effective and simple manner, which will be appreciated by those familiar with the care of and requirements attendant upon the nursing 125 of the sick.

Having thus fully described my invention, what I claim as new, and desire to secure by Letters Patent of the United States, is—

1. In an invalid bed, the hammock-frame 130 composed of detachable side and end bars arranged in rectangular form and provided with a removable covering hemmed along its edges; said hems being adapted to receive

the side and end bars of the frame, and detachable bolts for securing the overlapped ends of the frame-bars together, substantially as described.

5 2. In an invalid bed, the combination with the bedstead and the hoisting devices, of the hammock-frame composed of side and end bars detachably secured together by eye-bolts passing through their overlapped ends, and 10 the canvas removably attached thereto; said eye-bolts serving the double purpose of securing said bars together and providing detachable connections to the hoisting ropes, substantially as described.

15 3. In combination with the bedstead and the hoisting devices, the hammock-frame composed of side and end bars having their overlapped ends secured together by detachable eye-bolts, a supplemental head - frame constructed in like manner and hinged to said hammock-frame; and a covering of suitable material adapted to receive the side and end bars of the frames; said detachable eye-bolts serving the double purpose of securing the 25 frame bars together and receiving detachable connections on the ends of the hoisting ropes, substantially as described.

4. The combination of the folding or "knock-down" bedstead having posts at the 30 head and foot thereof, each provided with a

friction roll or sheave at or near its upper end, the shaft journaled in bearings secured to one pair of posts below the plane of the sheaves thereon and provided at one side of the bed with a gear-wheel, a locking pawl 35 engaging therewith, and a pinion meshing with said gear-wheel and provided with a crank-handle; a pair of sheaves journaled upon the opposite pair of posts below the plane of the upper sheaves thereon, the hammock - frame suspended by hoisting ropes which are secured to said shaft near its ends and pass over said sheaves, substantially as described, together with snap hooks on the free ends of the ropes engaging the eye-bolts 40 45 on the hammock-frame, all constructed and arranged substantially as described, so as to adapt both bed and frame to be readily folded into compact form for storage or transportation, and to enable a single attendant to readily and quickly adjust and secure the hammock-frame in various positions in use, substantially as described.

In testimony whereof I affix my signature in presence of two witnesses.
